UNITED STATES PATENT OFFICE

156,144

DESIGN FOR A BOTTOM FOR BOWLING BALL BAGS OR THE LIKE

Allan McConnell, Chicago, Ill., assignor to The Brunswick-Balke-Collender Company, Chicago,
Ill., a corporation of Delaware

Application May 11, 1948, Serial No. 146,291

Term of patent 14 years

(Cl. D58—4)

To all whom it may concern:

Be it known that I, Allan McConnell, a citizen of the United States, residing in the city of Chicago, in the county of Cook, State of Illinois, have invented a new, original, and ornamental Design for a Bottom for Bowling Ball Bags or the like, of which the following is a specification, reference being had to the accompanying drawings, forming a part thereof.

Fig. 1 is a top plan view of a bottom for a bowling ball bag or the like showing my new design;

Fig. 2 is an elevational view looking at the bottom edge of Fig. 1;

Fig. 3 is a bottom view thereof;

Fig. 4 is a sectional view along the line 4—4 of Fig. 1.

I claim:

The ornamental design for a bottom for bowling ball bags or the like, as shown.

ALLAN McCONNELL.
